UNITED STATES PATENT OFFICE

ALEXANDER H. HANDLAN, OF ST. LOUIS, MISSOURI

SIGNAL LAMP

Application filed February 20, 1926. Serial No. 89,576.

This invention relates generally to signal lamps, and more particularly to a signal lamp intended for use on railroad systems, the main object of the invention being to produce 5 a signal lamp having a base and a shell body provided with a plurality of lenses rotatable relative to said base. My improved signal lamp also includes means carried by the base thereof through the medium of which 10 rays of light from the light source within the lamp may be prevented from passing through certain of the lenses in the lamp shell according to the adjustment of the shell upon the base supporting it.

15 With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which 20 come within the scope of the claims hereunto 25 appended.

Fig. I is a side elevation of a signal lamp made in accordance with my invention.

Fig. II is a vertical section through the lamp shell in Fig. I.

30 Fig. III is a horizontal section taken through the lamp shown in Figs. I and II. In the drawing A designates the base of my improved signal lamp and B is the shell thereof. The shell B of my improved signal 35 lamp is spherical in shape and is provided with a plurality of lenses C, and said shell is also provided with a cover D at the top thereof which is hinged to the shell at the point indicated by the reference character 40 E. My signal lamp also includes a suitable fastening device F by means of which the cover D may be fastened in a closed position. Secured to and extended from the base A of the signal lamp is an arm G by means of 45 which said signal lamp may be secured to a suitable support when in service.

In the preferred construction of my improved signal lamp the base A comprises a plate circular in plan view and provided with 50 a depressed center portion A', as shown in Fig.

II. Arranged within the depressed portion of the base B is a socket B^a adapted to receive an electric lamp bulb which would function as the light source of the signal lamp, and B^c designates a switch mechanism by means of 55 which the operation of the light source may be controlled. The base B is provided with an aperture B' through which the operating arm B^d of the switch mechanism extends, so that the flow of electrical energy to the light 60 source may be controlled from the exterior of the signal lamp.

Extended outwardly from the base A at its lower face is an annular flange 1, upon the top face of which the lower face of the 65 wall of the shell B rests. As will be noted by referring to Fig. II, the depressed portion A' of the base A is surrounded by an upwardly extended annular portion 2, and said upwardly extended annular portion extends 70 into the lower portion of the lamp shell B, the circumferential face of said annular portion 2 contacting with the inner face of the wall of the shell. Formed in the circumferential face of the upwardly extended portion 75 2 of the base is an annular recess 3. 4 designates a pin or similar device which is extended through the wall of the shell B and into the annular recess 3, the particular device shown in the drawing being a screw 80 which is passed through a threaded opening in the wall of the shell. It is apparent when the screw 4 is in place as shown in Fig. II, that is, with the end portion of the screw 85 4 extending into the annular recess 3, that the shell B of the lamp is retained in its proper position with respect to the shell of the lamp, due to the fact that the screw 4 contacts with the top wall of the annular recess 3, whereby the shell may be rotated with respect to the base A but may not be moved upwardly with respect to the base A. The upper wall of the annular recess 90 95 3 is notched as indicated by the reference character 5, and when it is desired to remove the shell B from the base the lamp shell is moved to a position where the screw 4 is in vertical alinement with the notch 5, whereupon the shell may be moved upwardly with 100

respect to the base, said screw passing through said notch.

The shell of my lamp is provided with a plurality of lens openings that accommodate the lenses C, which may be of different colors or one or more of which may be uncolored while the remainder are colored. In the drawings I have shown four of such lenses, but it is obvious that the lamp may be supplied with a greater or less number of lenses.

To prevent the passage of rays of light from the light source within the lamp through any of the lenses C, I arrange within the lamp 15 a shield 6 which is supported by the base A and is of such dimensions as to prevent passage of rays of light from the light source through any of the lenses C when interposed between the light source and the lens. The 20 shield 6 is preferably of sheet metal and it is secured at its lower edge to the base A by any suitable fastening means, such as screws. The shield is arranged concentric with the lamp shell and therefore when said shell is rotated 25 upon the base A while said base remains stationary the lenses C may be so adjusted as to cause the shield to be interposed between the light source and any of the lenses through which it may be desired to prevent the passage of rays of light while permitting the passage of such rays of light through other lenses.

The rotatable lamp shell B is held in adjusted positions by a spring-governed latch 35 bolt 7 loosely arranged in a spring housing 8 fixed to the lamp shell opposite to the upwardly extended portion 2 of the base A. In said portion 2 of the base are horizontal bolt holes 9 adapted to receive the latch bolt 7 for the 40 purpose of holding the shell in predetermined positions and preventing rotation of said shell with relation to the base.

I claim:

1. In a signal lamp, a base member, a lamp shell member adapted to be rotatably supported by the base member, one of said members being provided with a peripheral groove having a channel communicating therewith, said peripheral groove being arranged at a true 50 right angle with respect to the major axis of said base, and a projection carried by the other of said members and adapted normally to extend into the groove to hold the base and the shell in interfitting relation, and movable 55 into alignment with the channel communicating with the groove to permit separation of the base and the shell.

2. In a signal lamp, a supporting base having an upright circumferential flange formed 60 thereon, a lamp shell having an annular base member adapted to overlie and interengage the upright flange on the supporting base, a member for use in producing rotation between the shell and the base, the member being adapted also to serve as a lock in

holding the shell and the base in a desired position of adjustment relatively one to the other, and a projection carried by the shell for engaging within a groove formed in the base at a true right angle with respect to the major axis thereof to maintain the base and the shell in interfitting relation, the projection being movable into alignment with a channel formed in the base to permit separation of the base and the shell.

In testimony that I claim the foregoing I 75
hereunto affix my signature.

ALEXANDER H. HANDLAN.
